UNITED STATES PATENT OFFICE.

SAMUEL FISHER, OF BALTIMORE, MARYLAND.

SPONGING MACHINE.

Application filed July 16, 1923. Serial No. 651,900.

To all whom it may concern:

Be it known that I, SAMUEL FISHER, a citizen of the United States, residing at Baltimore, in the county of Baltimore City and State of Maryland, have invented new and useful Improvements in Sponging Machines, of which the following is a specification.

My present invention has reference to 10 cloth sponging and pressing apparatus, and is to be considered in the nature of an improvement upon my co-pending application, Serial No. 620,992, filed February 24, 1923.

With the above broadly stated object in 15 view, and many others which will present themselves as the nature of the invention is better understood from the following detailed description, the improvement resides in the construction, combination and operative association of parts such as is disclosed by the drawings which accompany 20 and which form part of this application.

In the drawings:—

Figure 1 is a side elevation of a cloth 25 sponging and pressing machine in accordance with this invention.

Figure 2 is an end view thereof.

Figure 3 is a similar view but looking 30 toward the opposite end of the apparatus.

Figure 4 is a substantially central longitudinal sectional view through the cloth pressing rolls to illustrate the mounting as well as the steam inlet and outlet means therefor.

Figure 5 is a fragmentary enlarged sectional view through one end of the sponging drum and the mounting therefor.

Figure 6 is a sectional view approximately 35 on the line 6—6 of Figure 5.

Figure 7 is a fragmentary horizontal sectional view of the mounting for the feed roll, the roll being also in section.

As in my referred to pending application, Serial No. 620,992, I provide a table 1 45 which is supported on a frame that is made up of connected pipe sections. To the pipe sections that provide the corner posts of the frame I attach by suitable couplings transverse brace pipes 2 and 3 respectively. The 50 pipes 3 support thereon brackets 4 having elongated body portions that pass through openings in metal blocks 5 secured on the top adjacent to the ends of a steam generating tank 6. The tank, at one of its ends 55 is provided with a transparent water gauge 7, suitable cocks 8 being provided at the ends

of the gauge tube at the communication thereof with the generator. Thus, should the tube become broken, the cocks may be closed to prevent the escape of steam from 60 the generator. In addition to this, I arrange on the said end of the generating tank 6 try-out cocks 9 and 10 respectively. These cocks are disposed one above the other and are only opened in case of the breakage of 65 the gauge 7, although the said cocks may be opened to ascertain the level of water and steam in the tank.

Water is let into the bottom of the tank 70 through a pipe 11 which is connected with the house supply. The tank, at a suitable distance above its bottom is provided with a blow-out plug 12 designed as a safety device in case of an over-pressure of steam 75 in the tank.

On the end of the tank opposite that provided with the gauge and the cocks 9 and 10 there is a man-hole normally closed by a suitable cover 13 held tightly in place by adjustable means 14. By providing the 80 hanger brackets, as above described, tanks of varying sizes may be supported on the frame.

The water inlet pipe 11 has its passage 85 controlled by a valve 15, and the said pipe has therein, to one side of the valve 15, a check valve 16. The check valve is designed to admit water into the tank 6, but opens in a direction to prevent the passage of heated water or steam into the horizontal branch 90 of the inlet pipe 11. The horizontal branch of the inlet pipe is, as disclosed by the drawings, connected by a coupling to the vertical branch thereof, and to this coupling there is a short pipe extension having screwed on 95 its outer end a faucet 17. The faucet provides a drain for the tank when the valve 15 is closed.

Secured by couplings to the transverse pipes 2 and 3, there are depending pipe sections 18 and 19 respectively. The pipe 18 has therein a coupling to which is connected a short angle pipe, the latter having at its end a coupling to which is secured a depending short pipe 20. The pipes 18 and 20 100 have secured at their ends burner tubes 22 and 23 respectively. The tube 22 is supported from the lower end of the pipe member 19 and has a short pipe connection 24 with the end of the burner tube 23. The 110 outer end of the pipe 24 is capped, as clearly illustrated in Figure 3 of the drawings. The

tubes 22 and 23 have their gas outlet apertures arranged longitudinally to the sides of the upper center thereof, and the inlet end of each of the tubes is provided with a mixing chamber 25 in which enters the gas inlet pipes 26 connected to a branch or a gas supply pipe 27. The inlet pipes 26 are, of course, controlled by valves 28.

At one end the tank 6 has secured thereto 10 a communicating pipe arranged at an outward horizontal angle therefrom and terminating in an upright pipe 29 which projects a suitable distance above the table and is located to one side thereof adjacent to what 15 I will term the rear of the table. The pipe 29 has at its upper end a blow-off valve 30. In this manner, excess steam in the generating tank will find an outlet without liability of inflicting damage to the tank or to the 20 other parts of the apparatus. Upon its opposite end, there is also secured a rearwardly directed horizontally disposed pipe that terminates in an upright branch 31. The branch 31 is coiled upon itself, as at 32, and 25 from thence continued and has secured to its upper end a steam gauge 33. Water is let in the upper end of the pipe and rests in the coil 32. Steam from the boiler acting upon this body of water influences the same 30 to turn the hand of the gauge so that the operator can accurately determine the amount of pounds pressure of steam in the generating tank.

Certain of the legs or corner posts of the 35 frame are disposed outwardly with respect to the other corner legs. These legs, for distinction, are indicated by the numerals 34 and 35 respectively. The legs are provided with couplings whose central branch 36 underlies 40 and supports the outer end of the table 1. The legs 34 and 35 project a suitable distance above the top of the table and have at their upper ends couplings 37 and 38 respectively. The horizontal branch of one 45 of these couplings is notched, as at 40 (Figure 2). These couplings receive therein the ends of a rod 41. The ends are offset from the rod proper, and the purpose of this rod will hereinafter be set forth.

50 Connected by a coupling to the side brace pipe 2 of the frame there is a short plug pipe 42 whose outer end has secured thereon a T-coupling 43. The longer or longitudinal branch of the T-coupling is disposed 55 horizontally with respect to the frame, and has screwed therein a vertically disposed sectional pipe 44. The bottom of the coupling has screwed therein the nipple or neck of a valve 45. The valved end of the 60 pipe 44 communicates with the atmosphere. At its upper end, the pipe 44 has a coupling therein which provides a bearing for a shaft 46. On the outer end of this shaft there is a crank handle 47, and on the inner 65 end of the said shaft there is a flange that is

bolted or otherwise secured to one end of a hollow drum 48. The opposite closed end of the drum 48 is centrally provided with an opening surrounded by an inwardly directed flange in which there is received a bearing sleeve 49. The sleeve has its outer end threaded and has screwed thereon a packing nut 50 which forces a packing 51 against the outer end of the said sleeve. 70 Journaled in the sleeve there is a pipe section 52 that has screwed on its outer end a coupling 53. The central depending branch of the coupling is connected to a sectional pipe 54, similar to the pipe 44 and which has its lower end secured to the brace pipe 3 by suitable couplings. The upper end of the sectional pipe 54 is plugged, as at 55. Connected to the coupling 53 there is a pipe 56 which in turn is connected by a coupling to a vertically arranged depending pipe 57, the last mentioned pipe being connected by a coupling to a branch pipe 58 that communicates directly with the top of the generating tank 6. The pipe 57 has arranged therein a hand operated valve 59 which regulates the passage of steam through the upper portion thereof.

The drum 48 has its body portion provided with longitudinal series of spaced apertures 60, and arranged around the drum and secured thereto there is a fabric facing 61.

To the couplings at the upper ends of the sectional pipes 44 and 54 there are secured horizontally disposed inwardly extending short pipes 62 whose inner ends are plugged. To the plugs there are secured the ends of helical springs 63. The springs have their outer ends connected to means 64 in slidable pipe sections or tubes 65. The outer ends of the pipe members 63 are covered by cap nuts 66 through which the tubes 65 pass, and passing transversely through the outer ends of the tubes 65 are inwardly directed studs 67 that are received in the ends of a roller 68. The springs 63, influencing the tubes 65, will cause the roller 68 to frictionally engage with the fabric facing 61 of the apertured drum 48.

In the sectional pipes 44 and 54, at a suitable distance below the drum 48 there are opposed pairs of cross couplings 69, 69', 70 and 70'. The outer branch of the cross coupling 69 in the pipe 44 is plugged as is the vertical upper branch thereof. The inner longitudinal branch has screwed therein a pipe section 71 received in a sleeve 72 screwed in the inwardly directed flange 73 that surrounds a central opening in a hollow roller 74. On the outer end of the sleeve 72 there is screwed a packing nut 75 that forces a packing 76 against the sleeve 72. The inner longitudinal branch of the cross coupling 69' is similarly connected to a second hollow roller 77. The outer longi-

tudinal branch of the said coupling 69' has screwed therein a short pipe section having at its outer end a flanged nut 78 that forces packings against the said short pipe and 5 against an annular flange 79 on a shaft 80 that is received through the said nut and in the said short pipe. The shaft 80 has on its outer end a crank handle 81 and on its inner end a rod extension 82 to which is ad- 10 justably connected a spider 83 that is in contacting engagement with the bearing sleeve 72 in the roller 77. On the ends of the rollers 74 and 77 there are secured intermeshing gear wheels 84 and 85 respec- 15 tively.

The opposite ends of the hollow rollers 74 and 77 have inwardly directed flanges that surround central openings therein, and 20 screwed in these flanges there are tubes whose outer ends are engaged by packing nuts 86 and 87, respectively. Finding bearings in the sleeves there are short pipes which are connected to the inner branches 25 of the cross couplings 70 and 70', respectively. The nuts 86 and 87 force packings against the sleeves and against the mentioned short pipes. This portion of the construction is enclosed by a box 88 that is suitably supported against movement and that has 30 at its lower end an angularly arranged drain pipe 89. The box is provided to catch any leakage which may result between the joints above described.

The vertical branches of the cross couplings 70 and 70' are plugged. The outer longitudinal branch of the coupling 70 has secured therein a pipe 90 connected by a coupling to the steam conducting pipe 57. The outer longitudinal branch of the coupling 70' has connected therewith an angle pipe 91 whose depending branch has its passage controlled by a cock 92.

In the steam conducting pipe 57, below the pipe 90, there is a coupling 93 provided 45 with an angle branch to which is connected a short pipe having at its outer end a cock 94. In the horizontal branch 58 of the steam conducting pipe there is a T-coupling having its central branch upwardly directed 50 and having screwed therein a valve 95. The valve has connected to its upper end a funnel shaped member 96 arranged directly below the drain pipe 89, and the cock 92 and 94. The valve 95 is closed as long as the 55 device is in operation and receives drainage deposited into the funnel 96 incident to condensation in the hollow rollers 74 and 77 and in the steam conducting pipe 57. This drainage is allowed to pass from the funnel 60 through the pipe 58 into the generating tank 6 when the valve 59 is closed and the apparatus is idle. The cocks 92 and 94 are open just prior to the operation of the device so that all moisture may be drained from the 65 parts before steam is admitted into the drum

48 and into the rollers 74 and 77. It is important that the steam fed into these parts be in a perfectly dry condition.

The operation may be briefly described as follows: short lengths of cloth may be arranged on the table which will feed between the presser roller and the apertured drum 48 for the sponging operation, it being understood that steam is admitted to the drum. Should it be found desirable to 70 press such lengths of cloth, the same will feed from the drum between the pressing rollers 74 and 77, in which instance, steam is admitted into the said rollers. The steam is admitted through the valve controlled 75 branch 90 of the steam conducting pipe directly into the upper drum 74. The amount of steam in the rollers is controlled by regulating the valve 45. Thus should the valve 45 be entirely opened the steam will flow 80 directly through the roller 74 and find an outlet through the pipe 44 to the atmosphere and will not, to any extent, enter the lower roller 77. When the valve 45 is closed or almost closed the steam initially directed 85 into the upper drum 74 will be conducted into the roller 77 through the short pipe section 71, pipe 44 and the short pipe section between the coupling 69' and the roller 77, so that the pressure of steam in both the 90 rollers 74 and 77 will be approximately equal and both of the rollers heated to the same degree. In this manner fabrics of different characters or of different weaves will be properly pressed. Of course, the 100 crank handle 47 is operated to move the cloth around the drum, and the crank handle 81 is operated to turn the rollers in reverse directions in the pressing of the cloth. When bolts of cloth are to be pressed the 105 rod 41 is removed from its bearing brackets or couplings and passed centrally through the bolt. The rod with the bolt thereon again rests on its bearings, and the cloth is 110 fed between the drum and the spring influenced roller 68, which, of course, tightly forces the cloth in contact with the drum so that the cloth will be effectively sponged, when the drum is rotated. The cloth is then fed between the pressing rollers 74 and 77 so that the same is delivered onto the table in a perfectly smooth condition. The drum and the pressing rollers are 115 slowly revolved so that the cloth will receive the full benefit of the steam from the apertured drum 48 and properly pressed when passing between the pressing rollers. The treated cloth may be folded on the table or may be received on a clean sheet of 120 paper which is arranged on the frame.

It is believed that the foregoing description, when taken in connection with the drawings will fully set forth the construction and advantages of my improvement, 125 but it is to be understood that the nature 130

thereof is such as to render the same susceptible to such changes, form, construction and other modifications as fall within the scope of what I claim.

5 Having thus described the invention, I claim:—

1. In an apparatus for the purpose set forth, a frame supported table, a steam generating tank removably and adjustably secured thereon, a blow off plug in the tank, a blow off valve associated with the tank, a steam valve also associated with the tank, a water gage for the tank, try-out cocks for the tank, means for admitting water into the tank, a check valve controlling such means, an outlet cock associated with such means, heating means for the boiler, an apertured hollow drum revolvably supported above the table and having a fabric facing 10 against which cloth to be sponged is arranged, spring influenced means for forcing the cloth against the drum, a valve controlled pipe from the steam generator communicating with the drum, a valve controlled drain in said pipe, hollow rollers supported below the drum, intermeshing gears therefor, means for revolving the drum, means for revolving the rollers, valve controlled means for admitting steam from 15 the steam conducting pipe into the upper roller, means establishing a steam passage between the upper and lower roller, means regulating the admission of steam from the upper into the lower roller, means for draining condensation from said lower roller, a 20 funnel-shaped member receiving the condensation and connected with the steam conducting pipe and a valve controlling the passage between said condensation receiving member and said steam conducting pipe. 40

2. In an apparatus for the purpose set forth, a hollow apertured drum having a fabric facing and against which cloth to be pressed is arranged, a roller disposed longitudinally at one side of the drum, spring influenced means supporting the roller and forcing the same toward the drum and for pressing cloth between the roller and drum, means for revolving the drum, means for admitting dry steam under pressure to the drum, a rod designed to be received in a bolt of cloth removably supported below the drum, hollow rollers journaled in bearings below the drum, intermeshing gears between the rollers, packings between the rollers and the bearings therefor, a box arranged around the packings at one end of the rollers, a drain pipe therefor, means for admitting steam under pressure into the upper roller, means establishing a steam inlet between the upper and lower rollers, means regulating the admission of steam from the upper into the lower roller and for directing said steam from the upper roller into the atmosphere, means for revolving the rollers and a funnel-shaped drain receiver below the outlet and the drain pipe for the box and having a valve connection with the steam conducting means. 45 50 55 60 65

In testimony whereof I affix my signature. 70

SAMUEL FISHER.
